UNITED STATES PATENT OFFICE.

MARTIN PATREMIO, OF LODI, NEW JERSEY.

DESIGN FOR A BABY'S RATTLE.

56,887.

Specification for Design.

Patented Jan. 4, 1921.

Application filed June 18, 1920. Serial No. 390,042. Term of patent 3½ years.

To all whom it may concern:

Be it known that I, MARTIN PATREMIO, a citizen of the United States of America, residing at #13 Summer street, Lodi, New Jersey, have invented a new, original, and ornamental Design for Babies' Rattles, of which the following is a specification, reference being had to the accompanying drawing, forming part thereof.

Figure 1 is an elevation of a rattle showing the first one-half of my design lined for the several colors of a rainbow arranged from left to right in their respective order:

orange, yellow, green, light blue and dark blue colors.

Fig. 2 is an elevation of my design for a baby's rattle showing the other one-half similar to that shown in Fig. 1, except in this figure the surface of the rattle is lined for red, orange, yellow, and green.

Fig. 3 is a plan view of the rattle looking from the handle end downward.

I claim:

The ornamental design for a baby's rattle as shown.

MARTIN PATREMIO.
